(57) CLAIM

The ornamental design for a collapsible foot spa with massager, as shown and described.

DESCRIPTION

FIG. 1 is an enlarged top perspective view of a collapsible foot spa with massager, showing my new design;

FIG. 2 is an enlarged bottom perspective view thereof;

FIG. 3 is an enlarged front view thereof;

FIG. 4 is an enlarged rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1; and, FIG. 10 is an enlarged detail view of area 10 in FIG. 2.

The broken lines in the drawings illustrate the portions of the collapsible foot spa with massager, which form no part of the claimed design.

The dash-dot-dash broken lines encircling the enlarged views are for annotative purposes only and form no part of the claim thereof.
